CAP SEAL

Constantine Lisciani, Chicago, Ill., assignor to The Protectoseal Company, Chicago, Ill., a corporation of Illinois

Application September 17, 1953, Serial No. 380,849

2 Claims. (Cl. 220—46)

This invention relates to operating mechanisms for 15 spout closures of safety cans and more particularly to an improved spout closure and seal therefor.

With the earlier form of cap closures and seals in use with safety cans of the type as disclosed and claimed in the U. S. Patent to Lebus No. 2,574,876 granted November 13, 1951, the usual form of gaskets in the form of a gas-treated washer tended to become unsatisfactory after use with the high volatile and corrosive type of fluids which are disposed as waste in safety cans using the earlier form of cap seal. It is therefore, a principal object of the invention to provide a simple form of cap seal provided with resilient material to form a perfect seal and yet have sufficient resistance against the highly volatile fluids thus disposed.

Another object of the invention is to provide a simple cap seal which may be readily and economically manufactured in order that upon the cap seal becoming worn, the old cap seal may be replaced with a new one, and also to provide an improved cap seal which is replaceable with the cap seals already in use in the field.

Still another object of the invention is to incorporate in the cap seal of this type sealing material in sheet form, which is highly resistant to volatile and corrosive fluids disposed in safety cans of the type with which the cap seal of this invention is used.

Many other objects and advantages of the construction herein shown and described will be obvious to those skilled in the art from the disclosure herein given.

To this end, my invention consists in the novel construction, arrangement, and combination of parts herein shown and described, and more particularly pointed out in the claims.

In the drawings, wherein like reference characters indicate like or corresponding parts:

Fig. 1 is a view in elevation, in cross section, illustrating one form of the cap seal or closure applied to a spout for a safety can;

Fig. 2 is a view in elevation, in cross section, illustrating a modified form of cap seal or closure applied to a spout of a safety can; and

Fig. 3 is a bottom view of the closure of Fig. 1.

The improved cap seal or closure of my invention in one embodiment preferably comprises a metal cap-like member affixed to a stud for application to a lever-actuated operating mechanism for spout closures in which the lever-operating mechanism permits the spout closure to uniformly seat about the periphery of the open end of a spout of a safety can to which the closure is applied.

Instead of the usual cork or gas-treated seal formed of leather and the like material, the metal cap supports a resilient closure portion to support a thin sheet of material used as a seal which is highly resistant to the highly volatile fluids or liquids and corrosive liquids disposed within the safety can. In one embodiment, the metal closure member is annularly sealed to the sheet-like seal and backing with a crimped annular bead forming a tight seal

2

while in the other embodiment, the metal cap member is affixed to the backing member and sheet-like seal with an annular angular crimp.

Referring to the drawings, one embodiment of my improved cap seal 5 is shown operatively affixed to a closure carrying member 6 of a lever-actuated operating mechanism for spout closures of the type as disclosed and claimed in the U. S. Patent to Lebus No. 2,574,876 granted November 13, 1951, with the cap closure in its closed position upon the open end of a spout 7 of a safety can of the type disclosed in the aforementioned patent.

The cap seal 5 preferably comprises a closure member 8 having an annular peripheral edge 9 and an upraised center portion 10 provided with an opening 11 to receive a stud-like member 12. The stud-like member is formed with a hollow rivet-like portion 13 formed by turning the rivet-like portion to a size to enter the opening 11, and forming the hollow portion 14 by drilling the extended portion 13 before it has been riveted over or staked to the position shown in Fig. 1, affixing an annular portion 15 of the closure member to the stud-like member 12. In the position shown, the stud-like member and closure member are rigidly affixed together. Although it is preferred to form the stud-like member as described, it is within the scope of the invention that they may be suitably affixed in any conventional manner without departing from the scope of the invention.

The stud-like member 12 for the size of cap seal or closure described is preferably formed from five-sixteenth inch diameter, stainless steel rod, and drilled at 16 to receive a suitable securing means 17 in the form of a rivet as shown riveted to a dome-shaped end 18 of the closure carrying member 6. The rivet extends through holes suitably drilled or formed in the dome-shaped end as shown, and the ends of the rivet suitably formed with heads 19, as shown in Fig. 3. The size of the rivet and the hole 16 through which it extends provide sufficient clearance to provide a loose fit so that in the closed position of the closure carrying member 6 of the lever-actuated operating mechanism, the closure member will seal the spout opening and the spring-biased pressure applied to the closure carrying member applied by the inner face of this member to a rounded end 20 of the stud-like member 12 complementally formed to the inner surface 21 of the dome-shaped end.

The space within the closure member is of sufficient depth to receive a soft sealing rubber member 22, disk-like in shape. It is preferred to form the soft sealing member from material known as "Hycar" from .120 inch to .135 inch in thickness and of 55-65 durometer hardness. Another suitable form of material for this member can be neoprene, Thiokol, cork, composition, etc., each of which has high deterioration resistance. This member provides an inexpensive, resilient and soft seat for a sealing member 23. The sealing member is preferably formed from a soft-like material which is inexpensive and impervious to the various volatile and corrosive liquids and yet provides a tight seal for the spout opening, and conforms readily to the beaded edge 24 of the spout opening.

A preferred material is "Teflon" for the sealing member which is highly resistant to highly volatile liquids and corrosive liquids, and is a synthetic plastic material. The disk-like member is formed from substantially 0.008" thickness material but it can be satisfactorily made from substantially 0.001" to 0.030" material thickness. Other suitable synthetic elastomeric materials may be used without departing from the scope of the invention. In order to have a satisfactory cap seal, the material must have the qualities of a soft sealing rubber and the deterioration resistance of a synthetic material such as the preferred "Teflon" or "Kel-F." Although material of the type of

polyethylene plastics may be used, it has been found that it is not as impervious and as resistant as "Teflon" or "Kel-F." It is preferred to fabricate the sealing portion of the cap seal provided by the members 22 and 23 respectively from rubber and the synthetic plastic material rather than providing the entire thickness of the two members from a single thickness, for example, of one-eighth inch "Teflon." Formed in this manner from a single thickness, the expense of the seal thus formed would be prohibitive whereas if fabricated as disclosed, the disk of rubber and the thin sheet-like disk of "Teflon" are approximately within the same nominal cost. The members 8 and 12 are preferably formed from stainless steel, the stud member 12 being formed from five-sixteenth inch diameter stainless steel rod and the closure member 8 being formed from 26 gage (.019") stainless steel in sheet form. It is also to be understood that these members may be suitably formed from synthetic plastic materials, which would have substantially the same resistance to highly volatile and corrosive fluids as stainless steel. It is also to be understood that these members 8 and 12 may also be formed from sheet steel and suitably coated to have substantially the same resistance to the volatile and corrosive liquids as stainless steel without departing from the scope of the invention.

In assembling the individual parts to form the complete cap seal after the stud 12 has been staked, as described above, to the closure member 8 and with the annular periphery 9 as shown in the dotted position 9', the synthetic rubber gasket 22 formed from "Hycar" material is first assembled within the closure member after which the disk 23 of the synthetic plastic "Teflon" is applied. With the members assembled in this manner, the assembly is positioned within a suitable die and the extended edge of the annular periphery 9 from its dotted position 9' is rolled over to form an annular bead 25, and the inturned edge thereof is securely pressed into the peripheral edge of the member 23 in the annular indented position 26 and similarly indenting the member 22 annularly. Sufficient pressure is applied in forming the annular beads 25 to provide a tight seal between the inturned edge of the bead 25 and the member 23 as at 27. From the above disclosure, it is quite apparent that a very simple, economical, and sturdy cap seal is provided which has a sealing face which is impervious to corrosive and highly volatile inflammable fluids, and which will effectively seal the spout opening of a safety can. Although the cap seal has been particularly described for use with the spout opening of safety disposal cans or for spout openings for the discharge of corrosive and inflammable volatile liquids, it is within the scope of the invention that modifications thereof may be suitably adapted for use with other closures such as radiator caps and gas tank caps for automotive and the like vehicles.

Referring to Fig. 2, there is illustrated another embodiment of the invention and like or primed reference characters will indicate the same or similar parts. The particular difference of this embodiment over that of Fig. 1 is in the method of affixing the annular peripheral edge 9 to assemble the member 22 and the sealing member 23. In each embodiment, the members are similarly formed, the metal members being preferably formed from stainless steel and the sealing members 22 and 23 being respectively formed from synthetic rubber and plastic materials as previously described.

In assembling the members forming the cap seal, the members 22 and 23 are inserted within the closure member 8 with the annular peripheral edge 9 in its original drawn shape 9'. The assembled parts are then placed in a suitable die and the extended edge formed to the annular inturned angular position 25'. When formed in this manner, the abutting annular edge of the sealing member 23 is formed to the indented complementally formed shape 26', forming an annular tight seal 27'. In the forming operation, the soft backing member 22 is

complementally indented and compressed to receive the annular indentation 26' formed in the sealing member 23. In either of these embodiments, an effective seal is annularly provided between the members 22 and 23, and the corresponding annular periphery 9 at the annular seal provided which prevents any of the highly volatile liquids or corrosive liquids from entering the interior of the completed cap seal.

It is evident from the embodiments disclosed that an inexpensive, impervious, and tight and soft seal is provided for the spout opening of any safety disposal can using a spout closure with lever-actuated operating mechanism of the type with which it has been disclosed. It is also obvious that when the cap closure becomes worn so that the sealing member 23 is worn through, the entire cap seal of each of the embodiments may be readily replaced.

While I have illustrated several embodiments of a cap closure suitable for disposal cans and the like, it is to be understood that it is within the scope of the invention that the cap seals of this invention may be suitably formed into other shapes and forms and from other suitable materials to cooperate in the desired manner with other shapes of spout closures and fittings depending upon the particular application of the invention. It will be apparent from the above disclosure that I have provided cap closures which are relatively simple in construction, attractive in appearance, and which provide effective seals for closure to spout openings for disposal cans, the pouring spouts, and other forms of inlet or outlet openings to reservoirs requiring an effective seal.

Having thus described my invention, it is obvious that various immaterial modifications may be made in the same without departing from the spirit of my invention; hence, I do not wish to be understood as limiting myself to the exact form, construction, arrangement and combination of parts herein shown and described, and uses mentioned.

What I claim as new and desire to secure by Letters Patent is:

1. As an article of manufacture, a cap seal comprising a flat disk-like metal closure member provided with an annular peripheral member providing a space to receive a disk-like soft backing member having the qualities of a soft sealing rubber and deterioration resistance of a synthetic elastomeric material and substantially within the range of thickness from 0.120" to 0.135" and a disk-like synthetic plastic sealing member substantially within the range of thickness from 0.001" to 0.030" formed from a material resistant to volatile inflammable liquids and corrosive liquids in abutting relationship, and the annular peripheral edge inturned in abutting relationship contiguous to the outer periphery of the sealing member and the backing member, whereby a vapor tight seal is provided between the annular edge of the synthetic plastic sealing member and the closure member, and the sealing member and backing member are affixed to the closure member, said sealing member providing a sealing face which is impervious to volatile inflammable liquids and corrosive liquids, said inturned annular peripheral edge forming an annular bead with the said inturned edge thereof indenting the sealing member and the backing member providing the vapor tight seal, and affixing the members together.

2. As an article of manufacture, a cap seal comprising a flat disk-like metal closure member including an annular member forming an enclosed space, a soft backing member substantially within the range of thickness from 0.120" to 0.135" mounted within the space, a synthetic plastic sealing member having the qualities of a soft sealing rubber and deterioration resistance of a synthetic elastomeric material and substantially within the range of thickness from 0.001" to 0.030" complementally formed to the aforesaid soft backing member and highly resistive to volatile and corrosive liquids, and securing

means complementally formed to the periphery of the closure member and annularly engaging the face of the sealing member contiguous to the periphery thereof, affixing the soft backing member and the sealing member within the closure member in abutting relationship whereby the face of the sealing member provides a surface which is resistant to deterioration by volatile and corrosive liquids and a vapor tight seal is formed to volatile liquids between the outer periphery of any opening to which the seal is applied by the soft seat provided by the 10 soft backing member.
